(57) **CLAIM**

The ornamental design for a dual monitor as shown and described.

DESCRIPTION

FIG. 1 is a front, right, and top perspective view of a dual monitor, showing my new design;
FIG. 2 is a rear, left, and bottom perspective view thereof;
FIG. 3 is a front elevational view thereof;
FIG. 4 is a rear elevational view thereof;
FIG. 5 is a left elevational view thereof;
FIG. 6 is a right elevational view thereof;
FIG. 7 is a top plan view thereof;
FIG. 8 is a bottom plan view thereof;
FIG. 9 is a detailed view of the encircled portion “9” in FIG. 2;
FIG. 10 is an elevational view thereof when being folded; and,
FIG. 11 is a rear elevational view thereof when being folded. The dot-dash broken lines in FIGS. 2 and 9 denote the boundaries of the detailed areas and form no part of the claimed design. The even dash broken lines in the drawings are portions of the dual monitor that form no part of the claimed design.
